RAIL FASTENER

Cyrus H. Loutrel, South Orange, N. J., assignor
to The National Lock Washer Company,
Newark, N. J.

Application October 11, 1939, Serial No. 299,025

5 Claims. (Cl. 238—349)

This invention relates to means for holding rails to railroad cross-ties.

As a train passes over the track, there is what may be termed a wave motion set up in the rails, the amount of this motion depending upon the weight and speed of the cars as they pass over the rails, this motion being transmitted to the cross-ties supporting the rails. Where the rails are fastened to wooden cross-ties by spikes, the strain set up in the rails tends to loosen the spikes and exposes the wood around the spikes to the weather and other elements which accelerate the deterioration of the cross-ties.

It has been found, particularly with present-day rail traffic, that rails cannot be secured to the cross-ties so that there will be no relative motion between them. Therefore, it has been proposed to fasten the rails to the cross-ties through some more or less resilient means, and many types of resilient rail fasteners have been proposed, and it is this type of resilient fastener to which my present invention is directed.

Many of the resilient forms of fasteners go into the tie or are directly fastened thereto, or have one end of the fastener attached to the rail tie-plate which, in turn, is fastened or held to the cross-tie by spikes or screws driven or screwed into the cross-tie.

It is the principal object of my invention to provide a construction which will produce maximum cooperative relation between the resilient fastener and the rail cross-tie, and my improved form of rail fastener and its application will be readily understood by reference to the annexed drawing, wherein:

Figure 1 is a side view of the outside portion of a rail, the cross-tie bar or sleeper being shown in elevation.

Figure 2 is a cross-section through the rail of Figure 1 in front of the fastener and the cross-tie.

As shown in the drawing, 1 is a section of a rail having a flange 2 adapted to rest on a tie-plate 3 which in turn is fastened to a wooden cross-tie or sleeper 6 by means of suitable spikes 4 and 5. The rail 1 is held in place on the tie-plate 3 by means of a resilient member preferably in the form of a flat piece of metal suitable for taking a spring temper. The fastener has a central portion 7 which passes upwardly along the side of the cross-tie 6. The fastener also has an end 8 bent over to pass under the cross-tie 6 while its upper end terminates in a reverse bend, the first bend 9 passing somewhat longitudinally along the length of the tie-plate 3, and then the portion 10 is bent and twisted over and down across the flange 2 of the rail 1. Prefer-

ably, the end of the fastener is curved upwardly in the form of a lip 11 which engages the flange 2 of the rail.

While I have shown only one fastener, another may be used in reverse position on the opposite side of the cross-tie 6. Furthermore, it will be obvious that one or two of the fasteners may be used on the inside flange of the rail.

From the construction described, it will be seen that the fastener per se is made of one 10 piece of material and does not require to be fastened to the cross-tie 6, so that no time and labor is lost in performing operations on the cross-tie or the fastener to make the attachment between the two. By slipping one end of the 15 fastener underneath the cross-tie, the maximum reactive cooperation is obtained between the cross-tie and the rail.

What I claim is:

1. A rail fastener comprising a spring member 20 having; an arm extending under a rail-bed cross-tie, a portion extending from the arm upwardly along the side of said cross-tie and terminating generally in a reverse bend, first passing longitudinally over a tie-plate and then transversely 25 over and into engagement with the base flange of the rail.

2. A rail fastener comprising a spring member having; an arm extending under a rail-bed cross-tie, a portion extending from the arm upwardly 30 along the side of said cross-tie and terminating generally in a reverse bend, first passing longitudinally over a tie-plate and then transversely and downwardly over the base flange of the rail and having a curved lip engaging the base 35 flange of the rail.

3. A rail fastener comprising a flat spring having its central portion adapted to lie along the side of a rail cross-tie, with one end bent to extend under the tie and its other end bent 40 to pass over a part of the rail tie-plate, and then over and into engagement with the flange of the rail base.

4. A rail fastener comprising a flat spring having its central portion adapted to lie along the 45 side of a rail cross-tie, with one end bent to extend under the tie and its other end bent to pass over a part of the rail tie-plate, and then twisted through an angle so as to pass over the flange of the rail base and terminating in a lip 50 adapted to grip the said flange.

5. A rail fastener comprising a flat spring having its central portion extending alongside a cross-tie with one end adapted to pass under the cross-tie and the other end formed to engage the 55 rail base flange.

CYRUS H. LOUTREL.
